UNITED STATES PATENT OFFICE.

EDWARD H. BELDEN, OF TOLEDO, OHIO, ASSIGNOR TO THE WILLYS-OVERLAND COMPANY, OF TOLEDO, OHIO, A CORPORATION OF OHIO.

FOLDING SEAT.

Application filed October 9, 1919. Serial No. 329,430.

This invention relates to an improved folding seat structure particularly adapted for use in connection with vehicles such as automobiles and the like.

5 In the construction of vehicles of this character it is desirable to provide means whereby the ordinary seating capacity of the vehicle may be temporarily increased by means of suitably positioned folding seats capable 10 when not in use of being folded so as to take up a slight amount of space, and at the same time be entirely out of the way of the occupants of the vehicle while not detracting from the general appearance of the body 15 design.

One object of the invention is to provide a device of this character wherein the folding seat will in its folded position be merged into the outline of a body portion of the 20 automobile and thus not detract from the pleasing appearance of the design.

A further object of the invention is to provide a device of this character which is readily accessible and can be easily and quickly 25 placed in extended position or returned to its folded position without interference with the occupants of the vehicle.

A further object of the invention is to provide a hinged lid which in its folded position may be used as a toe-board and cover 30 for a storage recess, while in its extended position serve as an extra seat to increase the seating capacity of the vehicle.

Further objects of the invention relate to 35 economies of manufacture and details of construction as will hereinafter appear from the detailed description to follow.

The objects of the invention are accomplished in one instance by the devices and 40 means described in the following specification, but it is evident that the same may be varied widely without departing from the scope of the invention as pointed out in the appended claims. A structure constituting 45 one embodiment of the invention is illustrated in the accompanying drawings forming a part herewith in which:

Figure I is a perspective view of an automobile body showing the position of the 50 folding seat relative to the other parts of the body when the seat is in folded position.

Figure II is a detail perspective view of one form of the invention illustrating the position of the folding seat when extended.

Figure III is a transverse sectional view 55 through the vehicle body illustrating the folding seat shown in Figure II, in extending position and showing its relation to the front seat of the vehicle.

Figure IV is a detail perspective view of 60 a modified form of the invention, illustrating the position of the folding seat with respect to the remaining parts of the vehicle body when the seat is extended.

Figure V is a transverse sectional view 65 of the vehicle body, illustrating the position of the modified form of folding seat shown in Figure IV, with respect to the front seat of the vehicle.

Figure VI is a detail sectional view il- 70 lustrating the folding seat shown in Figures II and III when in folded position and the operating mechanism associated therewith.

Figure VII is a detail sectional view of 75 the modified form of seat illustrated in Figures IV and V, and showing the same in its folded position together with the supporting devices associated therewith.

In the embodiment of the invention illustrated herewith, 1 designates an automobile body of the usual or any ordinary construction which is provided with a front seat 2 and a rear seat 3 arranged in the manner ordinarily employed in devices of this character. The front seat 2 is provided with a 80 suitable supporting frame 4 sloping downwardly and rearwardly from the base portion of the seat 2 to the flooring 5 of the automobile. A recess 6 is thus formed beneath the front seat of the automobile which 85 is capable of being utilized in any desired manner as for the storage of various articles which it may be desired to transport. The central portion of the rearwardly sloping frame is cut away to provide an opening 90 from the rear seat to the recess formed beneath the front seat of the vehicle, and a closure 7 is provided which is capable of being utilized when in its folding position as a closure for the opening in the frame and 95 a foot rest, and which when in its extended position serves as an extra seat.

In the form of the invention illustrated in Figures II, III and VI, the folding seat 7 is pivotally secured to the lower edge of 100 the front seat by means of a plurality of suitable hinges 9 secured to the upper edge of the folding seat and to the lower portion 105

- 8 of the front seat in any suitable manner as by means of bolts 10, while the lower edge portion of the seat is adapted when in its folded position to rest against a suitable flange 11 secured to the flooring 5 of the automobile and forming a bearing for the edge of the seat whereby the same is supported in such a position as to permit its edge portions to suitably merge into the 5 downwardly and rearwardly sloping frame portions 4. When the seat 7 is in its extended position it is suitably supported by means of sets of links 13 and 14 having their adjacent end portions pivotally connected as 10 at 15 while the link 13 is pivoted to a bracket 16 secured to the floor of the vehicle and in a similar manner the link 14 has one end thereof pivotally secured to a bracket 17 carried by the outer edge portion of the seat. 15 The link 14 has an extension 18 projecting beyond the point of its pivotal connection with the link 13, and an out-turned lug 19 carried by the extension 18 serves as a stop for co-operation with the link 13 when the 20 seat is in its extended position to retain the seat substantially horizontal as illustrated in dotted lines in Figure VI, and prevent the same from becoming accidentally folded. It will be understood that any desired number 25 of hinges 9 may be employed for securing the upper edge portion of the seat to the lower edge 8 of the front seat, and a separate pintle may be employed with each set of hinges or a single rod may be passed 30 through the plurality of hinges to serve as a common pintle upon which the folding seat may rotate. It will also be understood that the supporting links 13 and 14, together with their associated parts are preferably 35 arranged in duplicate, one pair of the supporting links being provided for each end of the folding seat.
- In the embodiment of the invention illustrated in Figures IV, V and VII, the folding seat 7 is pivotally connected to the side edges 19 of the frame 4 by means of a plurality of parallel links comprising a pair of similar links 20 pivotally connected to the upper edge of the seat as at 21 and pivotally connected to the edge 19 of the frame as at 22. Each of these links 20 is provided with an angular extension 23 formed adjacent one end thereof which is adapted to co-operate with a stop 24 carried by the edge of the frame to prevent excessive movement of the link in one direction. A pair of pivotally connected links 25 and 26 are pivotally secured together as at 27 and arranged to connect the lower edge of the folding seat 60 with side edge portions of the seat frame at opposite ends of the folding seat, the link 25 being pivotally connected to the outer edge of the seat as at 28 while the link 26 is pivotally secured to a bracket 29 carried by the floor of the vehicle. The links 25 and 26 are provided with a lock joint at the point of pivotal connection whereby the pivotal movement of the links relative to each other is limited in one direction for the purpose of properly maintaining the folding seat in 70 extended position as illustrated in dotted lines in Figure VII.
- It will be seen from the above description that a simple and convenient form of folding seat is provided which is capable of being readily and easily placed in extended position and retained in such position until it becomes desirable to fold the same. Moreover, when the folding seat is in its folded position it merges into and forms a part of 80 the downwardly and rearwardly sloping frame portion 4 of the front seat whereby the operating parts are entirely concealed and positioned out of the way of the occupants of the vehicle, and the seat may serve 85 as a foot rest for the occupants of the rear seat.
- While I have shown and described in considerable detail a specific embodiment of my invention, it is to be understood that this 90 showing and description is illustrative only and for the purpose of rendering my invention more clear, and that I do not regard the invention as limited to the precise details of construction illustrated or described 95 except in so far as I have included such limitations within the terms of the following claims; in which it is my intention to claim all novelty inherent in my invention broadly as well as specifically. 100
- What I claim as new and desire to secure by Letters Patent is:—
1. In a body structure; a rear seat, a front seat having a downwardly and rearwardly sloping base portion, a panel forming a part 105 of the sloping base portion capable of being raised to form a third seat, said panel being substantially flush with adjacent parts of said base portion in the closed position, and having its outer face adapted to become 110 the top of said third seat.
  2. In a body structure, the combination of a rear seat, a front seat, a hinged panel extending downwardly and rearwardly from the rear of the front seat, said panel when 115 in folded position being adapted to form a foot rest and means for supporting the panel in substantially horizontal position to form an extra seat the top of which constitutes 120 the outer face of the panel in the closed position.
  3. In a body structure, a rear seat, a front seat provided with a compartment thereunder, a closure for the compartment hingedly connected at its upper edge to the front seat 125 and sloping rearwardly and downwardly, and means for supporting the closure in substantially horizontal position to form an extra seat, said supporting means extending from points intermediate the ends of the 130

closure on the under side thereof, to the body and adapted to be concealed within said compartment.

4. In a vehicle body, a front seat having a supporting frame forming a compartment beneath the seat, a tilting panel pivotally supported at its upper edge by the seat frame and sloping rearwardly and downwardly to form with the frame a cover for said compartment beneath the seat, means for supporting the panel in substantially horizontal position to form an extra seat, said supporting means being concealed within the compartment when said tilting panel is in its lowered position.

5. In a vehicle body, a seat having a supporting frame, a panel carried by the frame and normally extending downwardly and rearwardly from the lower edge of the seat to a point adjacent the floor of the vehicle

and forming with said frame a cover for a compartment beneath the seat, and means for supporting the panel in a substantially horizontal position to provide an extra seat the top of which constitutes the outer face of the panel in the closed position.

6. In a vehicle body, a front seat, a panel hinged at its upper edge and extending downwardly from the seat and rearwardly thereof an appreciable distance to a point adjacent the floor, whereby to form an inclined foot rest, supports for the panel mounted rearwardly of and in spaced relation to the seat, and pivoted connections between said supports and the panel adapted to support the latter in a substantially horizontal position, whereby to afford an extra seat within the body.

In testimony whereof I affix my signature.
EDWARD H. BELDEN.
